UNITED STATES PATENT OFFICE.

JOSEPH WERNDL, OF COFFEYVILLE, KANSAS.

GUN-STOCK ATTACHMENT.

1,307,529.

Specification of Letters Patent. Patented June 24, 1919.

Application filed February 7, 1919. Serial No. 275,560.

To all whom it may concern:

Be it known that I, JOSEPH WERNDL, a subject of Germany, (who has taken out his first papers as a citizen of the United States,) residing at Coffeyville, in the county of Montgomery and State of Kansas, have invented certain new and useful Improvements in Gun-Stock Attachments, of which the following is a specification.

10 This invention relates to fire arms, and more especially to stocks which are cushioned; and the object of the same is to provide a cushion at the rear end of the ordinary gun stock such as a fowling piece or a 15 rifle whereby the "kick" of the gun will be taken up before it reaches the shoulder of the marksman.

Further objects of the invention are to permit the escape of air so that the springs 20 alone serve to cushion the parts and to make a neat fit between the fixed and movable elements so as to exclude dirt, twigs, leaves, etc., and yet to provide for removing the entire structure from the gun stock when 25 necessary.

Details are set forth in the following specification and claim. Attention is invited to the drawings wherein—

Figure 1 is a side elevation of a gun stock 30 provided with my improvement.

Fig. 2 is a longitudinal section thereof on an enlarged scale, and

Fig. 3 is a cross section on the line 3—3 of Fig. 2.

35 The gun stock S is usually of wood. Instead of cutting out its rear end, I prefer to cut the same off at substantially right angles and provide it with a surrounding rabbet indicated at 1. At the rear extremity, I 40 bore or otherwise form a considerable cavity 2 and in the bottom of the cavity a plurality of sockets indicated at 3 and shown herein as two in number. A vent opening 4 leads from the cavity through one side of the 45 stock for a purpose yet to appear. Fixed across the rear end of the stock is what I will call the butt plate 5 which has perforations 6 opening into the cavity 2 and which is preferably provided with a 50 surrounding flange 7 through which pass screws or other fastening devices 8 for holding this plate in place. By preference the plate carries a frame indicated at 9, which is made of strap metal and fits within the walls of 55 the cavity so as to afford a lining therefor

when the parts are assembled as yet to be described.

A movable shoulder plate 15 overlies the fixed butt plate 5 and is also by preference provided with a flange 17 somewhat wider 60 than that of the other plate and adapted to overlie it slightly as seen in Fig. 2. In fact, this flange is so wide as to produce a considerable pocket between the plates in which air may trap, and therefore the perforations 6 and the vent 4 are provided to permit the escape of this air when the plates approach each other as described below. Projecting rigidly from the inner side of the movable plate 15 is a pair of plungers 65 10 passing through holes 11 in the fixed butt plate, then throughout the length of the frame 9 and through holes 13 in the front end of the latter, and extending into the sockets 3 as seen; and surrounding these 70 plungers within the frame are expansive coiled springs 14 whose inner ends rest against the front end of the frame and whose outer ends bear against washers 17 which latter in turn are held by pins 18 75 80 through the plungers just inside the fixed plate 5. The pins therefore serve as stops for limiting the movement of the springs and also as stops for limiting the outward movement of the plungers which would otherwise draw out of their holes 11 in the butt plate.

The parts when assembled stand as seen in Figs. 1 and 2. When now the marksman places the shoulder plate 15 against his 90 shoulder and fires the gun, the rebound causes the stock S to move quickly toward his shoulder. This carries with it the frame 9 which is rigidly attached to the butt plate 5, and the front end of this frame bears 95 on the front ends of the springs 14 so that the latter are compressed against the relatively fixed washers and pins. Meanwhile the outer flange 17 slides over the inner flange 7 and into the rabbet 1 as far as necessary, and the close fit of the flanges upon each other prevent the entrance of extraneous matter into the space between them and therefore into the space between the two plates. The entire attachment is neat in 100 105 appearance and simple in construction and adds little if any weight to the gun stock.

The foregoing description and the drawings have reference to what may be considered the preferred, or approved form of 110

my invention. It is to be understood that I may make such changes in construction and arrangement and combination of parts, materials, dimensions, et cetera, as may 5 prove expedient and fall within the scope of the appended claim.

Having thus fully described my invention, what I claim as new and desire to secure by Letters Patent is:—

- 10 The combination with a gun stock having a cavity in its rear end and sockets in its body at the bottom of the cavity, the stock having an air vent opening into said cavity and a rabbet around its rearmost portion; of a butt plate secured to the rear end of the stock and having perforations opening into said cavity, a frame carried by this plate and fitting the cavity, the front end of
- 15

the frame having holes opposite said sockets and the plate having holes alining therewith, 20 a shoulder plate having a flange slidably mounted over the fixed plate and movable into said rabbet, a pair of plungers projecting from this plate through the holes in the fixed plate and the holes in the frame into 25 said sockets, pins through these plungers, washers next the pins, and expansive springs coiled on the plungers between the washers and the inner end of the frame.

In testimony whereof I affix my signature 30 in presence of two witnesses.

JOSEPH WERNDL.
